UNITED STATES PATENT OFFICE.

CLARENCE H. BRYAN, OF CHICAGO, ILLINOIS, ASSIGNOR OF ONE-HALF TO HENRY K. HOLSMAN, OF CHICAGO, ILLINOIS.

LAMP FOR AUTOMOBILES, &c.

No. 910,268.

Specification of Letters Patent.

Patented Jan. 19, 1908.

Application filed May 23, 1908. Serial No. 434,470.

To all whom it may concern:

Be it known that I, CLARENCE H. BRYAN, a citizen of the United States, and a resident of Chicago, in the county of Cook and State 5 of Illinois, have invented certain new and useful Improvements in Lamps for Automobiles, &c., of which the following is a full, clear, and exact specification.

My invention is concerned with a novel 10 lamp designed especially for use in automobiles, but which may be adapted for use elsewhere.

It consists essentially in a lamp provided with two burners in proximity to each other, 15 one of which is associated with an oil receptacle and adjustable wick furnishing a relatively feeble and cheap illuminant, and the other with a powerful and more expensive illuminant, such as acetylene gas, which is 20 adapted to be turned on or off, as needed, from the seat of an automobile, while the other is allowed to burn constantly while the lamp is in use, acting, as it were, as a pilot light for the main or acetylene burner.

25 To illustrate my invention, I annex hereto a sheet of drawings, in which the same reference characters are used to designate identical parts in all the figures, of which,—

Figure 1 is a side elevation of a portion of 30 an automobile equipped with a lamp embodying my invention; and Fig. 2 is a side elevation of the lamp proper, with a portion of the casing broken away and the acetylene burner in section.

35 In carrying out my invention, a casing *a* of any ordinary construction may be employed, and in its embodiment I employ an oil receptacle *b*, which has the burner *c* in the casing in proper location relative to the reflector *d* and the bull's eye *e* which is customarily employed with automobile and similar lamps. Immediately adjacent the burner *c* and in close proximity to the reflector *d*, I locate a second burner *f*, which 40 is preferably a burner for acetylene gas, or some other gaseous illuminant which is capable of producing a powerful flame, and connected with this burner *f* is the stem *g* extending through the rear of the lamp and 45 provided with the nipple *h* by which it is connected by the tube *j* with the generator *k*, which is located near the seat *l* of the automobile, so that the valve *m* of the generator 50 can be operated by the driver to turn the acetylene light on or off without leaving his 55 seat. The lamps are customarily located on an automobile, as shown, at a position in front of the hood *n*, and at such a distance from the driver's seat that he cannot manipulate the oil burner without leaving his seat. 60

The operation of my improved device will be readily apparent: When starting on a trip at night, the oil burner *c* is ignited and set for as feeble an illumination as may be desired, it being understood, of course, that 65 any oil flame is relatively feeble in comparison with the acetylene flame. The driver from his seat can then turn the valve *m* to throw the generator into operation and allow the gas to flow to the burner *f*, where it 70 is ignited from the oil flame, and furnishes a powerful illumination when needed. If it is desired to cut off the powerful illumination, it can be effected from the driver's seat by closing the valve *m*, and when it is 75 to be thrown on again, it is only necessary to turn the valve, the gas, of course, being ignited from the flame of the burner *c*. If the generator should fail temporarily in its operation, as sometimes happens, when the 80 gas begins to flow again it will at once be ignited, thus presenting a marked improvement over the ordinary acetylene lamp unprovided with the auxiliary burner. The utility of such a lamp will be readily apparent, as when driving through the well 85 lighted streets of a city, or in the open on a moonlight night, the gas may be turned off, leaving only the lesser illumination necessary to comply with the laws regulating 90 their use. When ill lighted streets, or a stretch of forest road, are reached, the acetylene cock is turned on by the driver from his seat, and the gas is instantly ignited from the oil flame, thus furnishing a 95 powerful illumination instantly, when it is needed, and only for so long as it is needed, as the driver can turn it off without leaving his seat or stopping the car. In case the illuminant for either burner becomes exhausted, the supply of the other, being independent, will still be available. 100

While I have shown and described my invention as embodied in the form which I at present consider best adapted to carry out 105 its purposes, it will be understood that it is capable of some modification, and that I do not desire to be limited in the interpretation of the following claims except as may be necessitated by the state of the prior art. 110

What I claim as new, and desire to secure by Letters Patent of the United States, is:

1. In a carriage lamp, the combination with a lamp casing, of an illuminating oil burner therein, means for adjusting a wick in said burner, and an oil receptacle associated therewith into which the wick extends, the oil being adapted to burn constantly as an illuminating and pilot light, a gas burner in said casing adjacent to the oil burner so that gas starting to flow therefrom will be ignited by the pilot flame, and means for supplying gas to the burner and controlling said supply from a distance.
2. In a carriage lamp, the combination with a lamp casing, of an illuminating oil burner therein, means for adjusting a wick in said burner, and an oil receptacle associated therewith into which the wick extends, the oil being adapted to burn constantly as an illuminating and pilot light, an acetylene gas burner located in said casing adjacent to the oil burner so that gas starting to flow therefrom will be ignited by the pilot flame, a generator at a distance from the burner, connections between said generator and gas
3. In a carriage lamp, the combination with a lamp casing having a smoke flue at the top, a reflector at the back, a lens at the front, an illuminating oil burner between the lens and the reflector, means for adjusting a wick in said burner, an oil receptacle associated therewith into which the wick is adapted to extend, the oil being adapted to burn constantly as an illuminating and pilot light, a gas burner in said casing also between the lens and the reflector and adjacent to the oil burner so that gas starting to flow therefrom will be ignited by the pilot flame, and means for supplying gas to the burner and controlling said supply from a distance.

In witness whereof, I have hereunto set my hand and affixed my seal, this 21st day of May, A. D. 1908.

CLARENCE H. BRYAN. [L. s.]
